UNITED STATES PATENT OFFICE.

EDWARD F. KENNEDY, OF ANSONIA, CONNECTICUT.

STOP MECHANISM.

1,217,774.

Specification of Letters Patent. Patented Feb. 27, 1917.

Application filed April 29, 1914, Serial No. 835,206. Renewed November 29, 1916. Serial No. 134,310.

To all whom it may concern:

Be it known that I, EDWARD F. KENNEDY, a citizen of the United States, residing at Ansonia, in the county of New Haven and State of Connecticut, have invented certain new and useful Improvements in Stop Mechanism, of which the following is a specification, reference being had to the accompanying drawings.

This invention relates to certain improvements in stop mechanism; and the object of the invention is to provide a novel and improved device of this general character in combination with a rotary brush adapted to be rotated under the influence of a motor and whereby the rotation of such brush under the influence of the motor may be readily and conveniently controlled.

The invention consists in the details of construction and in the combination and arrangement of the several parts whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be better understood, I will now proceed to describe the same with reference to the accompanying drawings, wherein—

Figure 1 is a top plan view, with a part in section, of a stop mechanism constructed in accordance with an embodiment of my invention;

Fig. 2 is a vertical longitudinal section taken through the device as illustrated in Fig. 1 in close proximity to a side thereof; and

Fig. 3 is a fragmentary side elevational view, illustrating certain details of construction as herein embodied.

As disclosed in the accompanying drawings, 1 denotes a base of any ordinary or preferred construction having suitably secured thereto a casing 2 of any desired configuration and including a hinged cover 3 whereby access may be had within the casing, said hinged cover being also provided with a suitable opening or aperture 4 through which a peripheral portion of the cleaning brush 5 is adapted to be projected.

As herein disclosed, the brush 5 is carried by a shaft 6 removably supported within the side plates 7 of the casing 2 whereby

such brush may be readily removed or applied into operative position. As herein disclosed, the extremities of the shaft 6 are directed through the elongated open slots 8 produced in the side plates 7 and such extremities of the shaft are operatively engaged by the inverted hook members 9 pivotally secured to the inner faces of the side plates 7 whereby it will be readily perceived that such shaft 6 is effectively maintained in operative position under normal conditions.

The shaft 6 has suitably affixed thereto a pinion 10 in mesh with a large gear 11 carried by a second transverse shaft 12 operatively supported by the side plates 7. The shaft 12 is adapted to be rotated under the influence of the gear train 15 and the operating spring 16. A further detail of the mounting of the gear train 15 and the co-action therewith of the spring 16 is believed to be unnecessary as the same is substantially the same as a conventional clock mechanism.

The gear 11 has projecting laterally from one face thereof the equidistantly spaced pins 17 adapted to be engaged by the weighted rock arm 18 carried by the shaft 14, one extremity 19 of the shaft being projected exteriorly of the casing 2 and being provided with the finger piece or rock arm 20 whereby it will be readily perceived that the shaft 14 may be so rocked as to elevate the rock arm 18 out of the path of travel of the pin 17 whereby the gear 11 will be permitted to rotate under the influence of the spring 16 to impart rotation to the brush 5. The weight of the rock arm 18 will cause the same to automatically intersect the line of travel of the pins 17 when pressure on the finger piece or rock arm 20 is released whereby it will be readily observed that the brush 5 will be caused to rotate only during the interval it takes the pin 17 next adjacent to the pin released to engage the weighted arm 18.

While any means may be employed for limiting the movement of the rock arm 18, I find it of advantage to provide the side plates 7 adjacent the finger piece or rock arm 20 with the outwardly directed projection 21 with which such key will abut.

From the foregoing description, it is thought to be obvious that a stop mechanism constructed in accordance with my invention is of an extremely simple and comparatively inexpensive nature and is par-

ticularly well adapted for use by reason of the convenience and facility with which it may be assembled and by reason of the effectiveness with which it performs its functions, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice except as defined by the appended claims.

15 I claim:

1. A device of the character described including a casing, a shaft operatively supported by the casing, a gear train operatively engaged with the shaft for imparting axial rotation thereto, one of said gears being provided with projections, a shaft disposed transversely of the casing above the gear provided with the projections, a rock arm carried by the last named shaft engageable with the projections, a second rock arm carried by the last named shaft exteriorly of the casing for imparting axial rotation to said last named shaft, and means carried by the casing coacting with the second named rock arm for limiting the movement of the first rock arm relative to the gear with which said first rock arm coacts.
2. A device of the character described including a casing, a shaft operatively supported by the casing, a gear train operatively engaged with the shaft for imparting axial rotation thereto, one of said gears being provided with projections, a shaft disposed transversely of the casing above the gear provided with the projec-

tions, a rock arm carried by the last named shaft engageable with the projections, a second rock arm carried by the last named shaft exteriorly of the casing for imparting axial rotation to said last named shaft and terminating in advance of the forward face of the casing, and means carried by the casing coacting with the second named rock arm for limiting the movement of the first rock arm relative to the gear with which said first rock arm coacts, said first named rock arm being adapted to move in the opposite direction by gravity.

3. A device of the character described comprising a casing, a shaft operatively supported by the casing, a gear train operatively engaged with the shaft for imparting axial rotation thereto, one of said gears being provided with projections, a shaft disposed transversely of the casing above the gear provided with the projections, a rock arm carried by the last named shaft engageable with the projections, a second rock arm carried by the last named shaft exteriorly of the casing for imparting axial rotation to said last named shaft, means carried by the casing coacting with the second named rock arm for limiting the movement of the first rock arm relative to the gear with which said first rock arm coacts, and a weighted member carried by the first rock arm for normally maintaining the first rock arm at the limit of its movement toward the gear with which it coacts.

In testimony whereof I hereunto affix my signature in the presence of two witnesses.

EDWARD F. KENNEDY.
